(57) **CLAIM**

The ornamental design for a static mixer, as shown and described.

DESCRIPTION

FIG. 1 is a top perspective view of a static mixer;

FIG. 2 is an end elevation view thereof;

FIG. 3 is a top plan view thereof;

FIG. 4 is a side elevation view thereof;

FIG. 5 is a cross-section view taken from line 5-5 of FIG. 3;

FIG. 6 is an enlarged detail view of portion 6 of FIG. 4; and,

FIG. 7 is a bottom perspective view of FIG. 1.

The dot dash broken line indicates cutoff boundaries for enlarged detailed portion views and form no part of the claim.

1 Claim, 7 Drawing Sheets
